UNITED STATES PATENT OFFICE.

JOHN F. FARMER, OF INDIANAPOLIS, INDIANA.

COMBINATION MOTOR-VEHICLE LAMP.

Application filed August 11, 1925. Serial No. 49,593.

This invention relates to headlights for motor-vehicles and especially to the type of lamp that has a plurality of reflectors and electric lamps, the invention having reference more particularly to a lamp having means for providing a main light and a relatively smaller side-light, to illuminate a roadway without projecting dazzling light beams into the eyes of drivers approaching the headlight.

An object of the invention is to provide an improved motor-vehicle lamp that shall be of simple construction and not costly to manufacture, which shall be adapted to be applied to motor-vehicles without requiring material alteration of existing structures, and which may be safely used on various types of motor-vehicles.

Another object is to provide an improved electric lamp which shall be of such construction as to commonly furnish ample light broadly on a road, or more narrowly when approaching opposing motor-vehicles.

A further object is to provide an improved combination of headlights which shall have improved efficiency in projecting light rays at various angles relatively to the line of movement, and whereby safe operation of motor-vehicles at night may be assured.

With the above-mentioned and other objects in view, the invention consists principally in a combination electrical lamp having a main reflector and lamp and a relatively smaller reflector of novel form and arrangement, so shielded as to prevent strong light beams reflected by it from being projected to the side of the road traversed by approaching motor-vehicles; and the invention consists also further in the novel parts and combinations thereof, and in a combination and arrangement of lamps and reflectors as hereinafter particularly described and further definitely claimed.

Referring to the drawings,—Figure 1 is a fragmentary top plan of the forward portion of a motor-vehicle having the improved lamps which are illustrated by horizontal central sections thereof; Fig. 2 is a front view of the improved side light reflector on an enlarged scale; Fig. 3 is a fragmentary front elevation of a motor-vehicle by which the arrangement of the improved lamps is shown; Fig. 4 is a horizontal central longitudinal section of the improved side light reflector on an enlarged scale; Fig. 5 is a transverse section of the improved lamp casing; and Fig. 6 is a horizontal fragmentary section on an enlarged scale showing means for adjusting and holding one of the headlight reflectors.

In the different figures of the drawings similar reference characters indicate corresponding elements or features of construction herein referred to in detail.

The invention can be best understood by reference to well-known parts of a motor-vehicle, particularly the forward axle 1 and wheels 2 and 3, frame members 4 and 5, the engine radiator 6, and suitable lamp stands 7 and 8 which are shown as supported by the frame members but obviously may be variously supported and shaped accordingly. For the purposes of the present invention each lamp stand has a saddle 9 on its top to directly support a lamp casing.

Each lamp casing is designed to be invertible so that the direction of side light rays may be changed in a simple manner, and permitting the lamps to be used either on one side or the opposite side of the motor-vehicle. One lamp casing comprises a main portion 10 which preferably is cylindrical and has a back portion 11, the main portion having bolt holes 12 in its under side and similar holes 12' in its opposite upper side to receive bolts 13 for securing it upon the saddle 9 and permitting it to be inverted. A main reflector 4 is arranged in the forward portion of the casing and has its front portion secured to the casing by means of a suitable frame 15 which holds a suitable lens 16 on the front of the reflector. The central portion of the reflector has a lamp socket 17 to which an electric lamp or bulb 18 is connected and supplied with current through a circuit 19 connected with the socket and extending through a bushing 20 with which the casing back 11 preferably is provided. This structure as will appear is suited for the left-hand lamp, and the right-hand lamp is mainly similar thereto and comprises a casing main portion 10' and a back portion 11' secured in place by means of bolts 13', a main reflector 14' secured in place by a suitable frame 15' which holds a lens 16' in place, the reflector having a lamp socket 17' supporting an electric lamp 18' that is supplied with current through a circuit 19' extending through a bushing 20'.

The casing 10 has a side frame 21 that

is angular relatively to the casing, the rearward portion of the frame being wider than the forward so as to extend out further from the casing than the forward portion of the 5 frame, and the frame has a glass front 22 which preferably is oblong so as to be longer horizontally than vertically, being preferably composed of window glass. In conformity to present road rules requiring driving 10 on the right-hand side of roads, the casing 10 is set so that the side frame shall be on the inner portion of the casing or towards the opposite casing 10', the latter having a side frame 21' arranged on the side 15 towards the casing 10 and provided with a front glass 23 which preferably is square in plan or may be circular if desired.

A novel reflector 24 is provided which is arranged partially in the casing 10 and partially 20 in the rearward portion of the frame 21, and is suitably supported in place to project a light beam forward approximately in parallelism with the beam projected by the main reflector 14. Preferably the reflector 25 is parabolic and adjustably supported, being provided with a hinge 25 on its outer portion, the hinge being supported on the inner side of the frame 21 adjacent to the glass front. The reflector may be variously 30 secured to prevent movement when adjusted on its hinge, a screw-threaded adjusting rod 26 preferably being secured to the back of the reflector and extending through the adjacent portion of the frame, being provided 35 with nuts 27 to adjustably secured the rod to the frame. Preferably the outer portion of the reflector adjacent to the hinge has a small lip 28 thereon projecting inwardly. The reflector has an extension 29 on its inner side portion that extends towards the 40 back of the main reflector 14 to reflect light rays laterally through the window glass 22, the lip 28 deflecting light rays towards the extension 29. The reflector is provided in 45 its central portion with a lamp socket 30 which supports an electric lamp or bulb 31, the reflector having a central opening 32 in which the socket is secured, and the lamp is supplied with current through a flexible circuit 33 that extends out through the bushing 20. The reflector 34 which is arranged 50 in the frame 21' has a central lamp socket 30' supporting a lamp 31' supplied with current through a flexible circuit 33' extending out through the bushing 20', a lamp 31' being supported by the socket. The reflector 34 preferably is shallow, having less depth than the reflector 24, so as to not project a strong light beam, being preferred 55 to reflect light rays broadly across the road and not seriously affect a driver looking into the reflector. Preferably the reflector is adjustably supported, as by means of a hinge 35 secured to the back of the reflector and 60 to the inner side of the rearward wide portion 65

of the frame 21', and held in position by means of an arm 36 secured to the back of the reflector, a screw-threaded rod 37 suitably connected to the arm and extending through the back portion of the frame, the wall of the frame preferably having a screw-threaded boss 38 fixed thereto, a lock nut 39 preferably being arranged on the rod. Preferably a coil spring 40 is supported by the frame and is seated under compression 70 against the arm 36, when the rod has a simple head on it engaging the opposite side of the arm, so that the rod may readily be turned to adjust the reflector. The adjusting devices obviously may be variously modified, as, for example the rod may be fixed rigidly to the arm 36 or directly to the reflector and extend through a plain hole in the casing frame and be adjustably secured in place by nuts on opposite sides of the 80 wall of the frame. It should be understood that the side reflectors are not in every case adjustably supported, and that each lamp casing may be supported in relatively inverted position to that shown when desired 85 to project the light rays laterally in the directions opposite to that indicated; as shown, the rays reflected from the reflector 24 and its extension being approximately between the broken lines 41 and 42, the rays 90 from the reflector 34 being approximately between the broken lines 43 and 44. It will be understood also that the current for the electric lamps may be variously supplied and the circuits provided with such switches as 95 may be desired.

In practical use, the main reflector and the lamp therein commonly illuminate the road ahead of the motor-vehicle but should be switched off upon the approach of an opposing driver, the side lights being immediately switched on, or may be constantly in use to augment the light from the main reflectors and lamps. The rays from the side lamp 31 are projected sufficiently forward to afford light for the driver while the lamp cannot be seen by an opposing driver, light rays being reflected laterally by the extension 29 to afford light on the right-hand side of the road when making right-hand turns. The reflector 34 projects sufficient light rays to the left-hand side of the road to safely permit left-hand turns and also lights the road in front of opposing motor-vehicles, there being no blinding light 115 from the reflector 34 into the eyes of an approaching driver. This arrangement permits safe driving at night at reasonable speed and without annoyance to other drivers.

What is claimed as new is:

1. A combination motor-vehicle lamp including a main reflector and a parabolic side reflector arranged to project light beams forwardly approximately in parallelism, the

side reflector having a longitudinally curved extension on and integral with its inner side terminating behind the main reflector to reflect diffused light rays forwardly horizontally and having also an inwardly-extending relatively short lip on its horizontally opposite side to deflect light rays towards the end of the reflector extension.

2. In a motor-vehicle lamp, a reflector comprising a parabolic portion and a longitudinally curved extension integral with one portion of the edge of the parabolic portion, the extension being curved transversely, and a relatively small lip on the opposite portion of the edge of the parabolic reflector integral therewith and projecting obtusely towards the end of the extension.

3. In a motor-vehicle lamp, the combination of a casing with a side window frame,

the normally rearward portion of the frame 20 being broader than the forward portion, a parabolic reflector arranged partially in the casing and having a longitudinally curved extension integral with the edge thereof and located in the casing, the opposite portion 25 of the reflector being in the frame and having a lip on its edge extending obliquely towards the end of the extension, a hinge secured to the inner side of the rearward portion of the frame and connected to the 30 reflector adjacent to said lip, an arm secured to the back of the reflector, and an adjusting screw connected to said arm and to the rearward portion of said frame.

In testimony whereof, I affix my signature 35 on the 7th day of August, 1925.

JOHN F. FARMER.
